United States Patent Office.

JONATHAN PICKERING, OF STOCKTON-ON-TEES, ENGLAND.

Letters Patent No. 99,231, dated January 25, 1870.

IMPROVED APPARATUS FOR RAISING AND LOWERING WEIGHTS.

The Schedule referred to in these Letters Patent and making part of the same.

To all whom it may concern:

Be it known that I, JONATHAN PICKERING, of Stockton-on-Tees, in the county of Durham, England, have invented certain Improvements in Apparatus for Raising Weights or Hoists, of which the following is a specification, reference being had to the accompanying drawings, like letters indicating like parts wherever they occur.

My invention consists in the novel construction and arrangements of two wheels or pulleys, of unequal diameters, with sunken chambers on their peripheries on the same spindle, and in placing over the larger wheel an endless chain, and over the smaller one a single chain, each chain having links of the requisite size to fit into the chambers, and then mounting the whole in a frame, so as to form a simple, compact, and convenient hoist, that can be readily used, where more complicated apparatus, such as was patented to me, December 1, 1868, cannot be employed.

In the drawings—

Figure 1 is a side elevation of my simple hoist;

Figure 2 is an edge view, showing the sunken chambers in the peripheries of the wheels;

Figure 3 is an elevation, showing how ratchet-wheels and pawls may be applied;

Figure 4 is a plan of fig. 3; and

Figure 5 represents the wheels apart on the same spindle.

The object of my invention is to produce a safe, simple, and convenient hoist. To accomplish this, I make two wheels or pulleys, A and B, of unequal diameters, with a deep groove, c, and a series of oblong sunken chambers, a, separated by short curved spurs, b, on their peripheries, as clearly shown in figs. 2, 4, and 5, and firmly secure them on the same spindle, D, and mount them into a frame, C, having a hook, E, at the top, for suspending the pulley-block thus constructed, as shown in fig. 1.

Over the wheels A and B, I place chains F and G, having their links so constructed that every alternate link may stand vertically in the grooves c, and the connecting ones lie flat in the oblong chambers a, and bear against the intervening spurs b.

The chain F, which passes over the larger wheel A, is endless, while the chain G, which passes over the smaller, is a single one.

In operating my device, the weight to be raised is attached to one end of the single chain, and the weight is raised by turning the larger wheel, by means of the endless chain G, the difference in diameter of the wheels giving the leverage which enables a light weight on the endless chain to counterbalance a heavy one on the single chain. When the wheels are thus moved, it will be seen that it will be impossible for the chains to slip, as they fit closely into the grooves and chambers on their peripheries.

It is obvious that these wheels may be provided with ratchet-wheels, H, and pawls, I, arranged to be operated by cords, d, as clearly shown in figs. 3 and 4, for the purpose of holding the weight in any desired position; and, further, that instead of having the wheels A and B close together, and mounted in a frame, so as to form a block, for suspension, they may be placed at some distance apart on the spindle D, and the spindle have its bearings in supports or uprights J, as clearly shown in fig. 5.

It will thus be seen that my hoist is simple, compact, and strong, and that it can be used in places where barrel, drum, and pulleys could not be so conveniently or readily fixed or hung.

Having thus described my invention,

What I claim, is—

A hoist, consisting of frame C, spindle D, and the wheels A and B, having their peripheries provided with chambers, a, when constructed and arranged to operate in connection with chains F and G, substantially as herein described.

In witness whereof, I, the said JONATHAN PICKERING, have hereunto set my hand, this 15th day of November, in the year of our Lord 1869.

JONATHAN PICKERING.

Witnesses:

WM. SHARPE, Attorney's Clerk,
Stockton-on-Tees, County of Durham, England.

JAMES TWEEDY, Attorney's Clerk,
Stockton-on-Tees aforesaid.
